ESCUTCHEON PLATE

Raymond U. H. Tegner, Lodi, Wis., assignor to
Amerock Corporation, Rockford, Ill.

Original design application Jan. 10, 1972, Ser. No.
216,871. Divided and this application Apr. 30,
1973, Ser. No. 355,329

Term of patent 14 years

Int. Cl. D8—09

U.S. Cl. D8—188

FIG. 1 is a side view of an escutcheon plate incorporating my new design and embodied in a plate for an entry lever.

FIG. 2 is a front view of the plate shown in FIG. 1 and taken along the line 2—2 in FIG. 1.

FIG. 3 is a sectional view taken along the line 3—3 in FIG. 2.

FIG. 4 is a sectional view taken along the line 4—4 in FIG. 2.

The portion shown in broken lines forms no part of the design.

This application is a division of my copending application Ser. No. 216,871, filed Jan. 10, 1972.

I claim:

The ornamental design for an escutcheon plate, as shown and described.
